UNITED STATES PATENT OFFICE.

CHARLES L. BROWN, OF ROBINSON, KANSAS.

BOX-FORMING MACHINE.

1,375,275.

Specification of Letters Patent. Patented Apr. 19, 1921.

Application filed September 8, 1920. Serial No. 408,920.

To all whom it may concern:

Be it known that I, CHARLES L. BROWN, a citizen of the United States, residing at Robinson, in the county of Brown, State 5 of Kansas, have invented a new and useful Box-Forming Machine; and I do hereby declare the following to be a full, clear, and exact description of the invention, such as will enable others skilled in the art to which 10 it appertains to make and use the same.

The invention relates to box forming machines and has for its object to provide a device of this character comprising a base member having adjustably mounted thereon 15 brackets for engaging the sides of the ends and partition members of a box and to provide a longitudinally movable bar slidably mounted in the base and provided with brackets which are adjustably mounted 20 thereon and are provided with spring actuated members for engaging the end and partition members of the box for holding said end and partition members in engagement 25 with the adjustable brackets carried by the base, so that a box may be easily formed.

A further object is to provide spring means for normally holding the slidable bar and its adjustable brackets out of clamping 30 engagement with the end and partition members, and to provide pivoted link members whereby the slidable bar may be forced longitudinally against the action of its spring.

With the above and other objects in view the invention resides in the combination and arrangement of parts as hereinafter set forth, shown in the drawings, described and claimed, it being understood that changes in 35 the precise embodiment of the invention may be made within the scope of what is claimed without departing from the spirit of the invention.

In the drawings:—

Figure 1 is a side elevation of the box forming machine.

Fig. 2 is a top plan view of the box forming machine.

Fig. 3 is a vertical longitudinal sectional view through one end of the box forming machine.

Fig. 4 is an end view.

Referring to the drawings, the numeral 1 designates the base of the machine and comprises spaced members 2, which spaced members are held in spaced relation to each

other by means of transversely disposed members 3. The members 2 at points substantially centrally thereof are provided with longitudinally disposed elongated slots 4, in which slots the brackets 5 are adjustably secured by means of bolts 6. Brackets 5 are adapted to be adjusted according to the length of box being formed and also to the position of the central partition 7 in relation to the ends 8 of the box. Slidably mounted between the spaced bars 2 is a slid- 65 able bar 9, to one end of which is connected as at 10 a coiled spring 11, the other end of said coiled spring being connected as at 12 to one of the cross members 3. The coiled spring normally moves the slidable bar 9 in the direction of the arrow *a* and therefore holds the partition and end engaging members normally out of engagement with the 70 partition 7 and ends 8. The brackets 13 are adjustably mounted in the slidable bar 9 by means of bolts 14 which pass through the brackets and the elongated slot 15 in the slidable bar. It will be seen that by 75 adjusting the brackets 13 in relation to the brackets 5 that various thicknesses of partition and end pieces may be accommodated and also that the clamping power of the spring actuated members 16, which are 80 forced into engagement with the end and partition members of the crate may be ad- 85 justed as desired. The spring actuated members 16 are provided with lugs 17, which lugs pass through apertures in the brackets 90 13 and have threaded on their end nuts 18 by means of which nuts the relation of the spring actuated clamping member 16 in re- 95 lation to the bracket 13 may be regulated.

Pivots connected as at 19 to the end 20 of the slidable bar 9 are links 21, the rear ends of said links having pivoted thereto as at 22 a second pair of links 23, which second pair of links have their other ends pivoted in a bracket 24 carried by the base 1 of the 100 machine. Pivoted to the links 21 and 23 at their pivotal points 22 is a pivoted handle member 25, said handle member forming means whereby the operator may force the adjacent ends of the links 21 and 23 down- 105 wardly into alignment with each other, thereby causing the slidable bar 9 to be moved to the full line position shown in Fig. 3 and consequently causing the end and partition members 8 and 7 of the box or 110 crate that is being formed to be securely clamped and held between the brackets 5 and

the spring actuated members 16. When the links 21 and 23 are in alinement with each other, it will be seen that the slidable bar 9 will be held against the movement in the direction of the arrow α under the influence of the spring 11. When it is desired to allow the spring 11 to move the slidable bar 9 in the direction of the arrow α an upward pull is imparted on the handle member 25, 10 or if so desired the handle member being pivoted at a point 22, it may be simply tilted until it engages the pin 26 thereby causing the pivotal point 22 to move upwardly to the dotted line position shown in Fig. 3. 15 When this is done the spring actuated clamping members 16 are moved out of engagement with the ends 8 of the partition 7. When it is desired to form a box the partition 7 and the ends are placed in the positions shown in Fig. 1, that is after the brackets have been properly adjusted for the length of box desired. The handle member 25 when forced downwardly will cause partition member 7 and the end members 8 to be securely clamped, thereby allowing side and bottom strips to be secured to the partition and end pieces 7 and 8.

The invention having been set forth what is claimed as new and useful is:—

- 30 1. A box forming machine comprising a base, brackets carried by said base, a slid-
able bar slidably mounted in the base, brackets carried by said slidable bar and
adapted to coöperate with the brackets car-
ried by the base, said slidable bar being
horizontally disposed, a coiled spring con-
nected to one end of the slidable bar and
to the base for normally holding the slidable
bar and its brackets out of operative pos-
ition, link connections comprising a pair of
links pivoted together and having their
other ends pivoted to the base and to the end
of the slidable bar, said link connections

when in alinement forcing the brackets car-
ried by the slidable bar and the base into 45
clamping position, and a handle pivoted to
the links at their point of pivotal connection
to each other, said handle extending up-
wardly where it can be readily grasped by
the operator. 50

2. A box forming machine comprising a base, longitudinally adjustable brackets dis-
posed on each side of the base and adapted
to engage one side of an article, a slidable bar
slidably mounted in the base, longitudinally 55
adjustable brackets carried by said bar, spring
actuated members carried by the brackets of
the adjustable bar and adapted to be forced
into and out of engagement with articles
which are in engagement with the brackets
of the base, a spring connected to one end of
the bar and to the base for normally holding
the spring actuated members out of 60
engagement with the articles being held, a
pair of links pivoted together and having
one of their ends pivoted to the base, the
other end of one of the links being pivoted
to the slidable bar, a handle member pivoted
to the links at their pivotal point and
extending upwardly, said handle member 65
forming means whereby on a downward
movement of the same the links may be
forced into alinement for moving the slid-
able bar during a clamping operation and
out of alinement on an upward movement 70
for allowing the spring to move the slidable
bar in the opposite direction during an un-
clamping operation. 75

In testimony whereof I have signed my
name to this specification in the presence of 80
two subscribing witnesses.

CHARLES L. BROWN.
